PEAK SHAVING GAS MIXING CONTROL SYSTEM

Edwin X. Schmidt, Nashotah, Wis., assignor to Cutler-Hammer, Inc., Milwaukee, Wis., a corporation of Delaware

Application February 6, 1952, Serial No. 270,244

6 Claims. (Cl. 137—90)

1

This invention relates to a peak shaving gas mixing control system.

Operation of a peak shaving gas mixing plant over a relatively long period of time on a fixed schedule of 10% or less of peak shaving gas by volume in the final gas mixture is advantageous. Such operation affords the most economical use of auxiliary gas consistent with satisfactory consumer appliance utilization. The copending Schmidt and Warner application Serial No. 652,431, filed March 6, 1946, now U. S. Patent 2,608,199, granted August 26, 1952, discloses a peak shaving gas mixing apparatus which is particularly adapted to such operation.

The present invention has as one of its primary objects to provide an improved peak shaving gas mixing plant control system affording the aforementioned type of operation.

Another object is to provide a control system which normally functions to maintain peak shaving gas mixing at a predetermined fixed volumetric basis and which functions in response to failure or deficiency of base gas supply to afford supply of peak shaving gas on a 100% or increased percentage basis and at a heating value insuring satisfactory consumer appliance utilization, and

Another object is to provide a system of the aforementioned character including calorimetric control and indicating means of a novel type.

Other objects and advantages of the invention will hereinafter appear.

The accompanying drawing illustrates a preferred embodiment of the invention which will now be described, it being understood that the embodiment disclosed is susceptible of various modifications in respect of details without departing from the scope of the appended claims.

The single figure of the drawing illustrates schematically and diagrammatically a fully automatic peak shaving gas mixing control system constructed in accordance with the invention.

Referring to the drawing, the numeral 5 designates a conduit through which a base gas, such as natural gas or carbureted water gas, is adapted to flow. Conduit 5 is provided with a metering device in the form of a fixed orifice 6. Any suitable means (not shown) may be employed for insuring maintenance of a predetermined pressure of the base gas at the upstream side of orifice 6, whereby a predetermined lower pressure will normally be provided on the downstream side of said orifice. By way of example let it be assumed that the base gas flowing in conduit 5 has a total heating value of 540 B. t. u.

per cubic foot. Conduit 5 at the downstream side of orifice 6 merges with a conduit 7 which may be assumed to be connected with a distribution system.

Peak shaving gas, such as propane, may be assumed to be supplied from any suitable source (not shown) at a fixed supply pressure to a conduit 8 which is connected to conduit 7 through a conduit 9. Conduit 8 has associated therewith a by-pass conduit 10.

Air may be assumed to be supplied from any suitable source (not shown) at a fixed supply pressure to a conduit 11, which merges with conduit 9. As will be appreciated the peak shaving gas and air flowing in conduits 8 and 11 mix in conduit 9 to form a peak shaving gas-air mixture which flows into conduit 7 to supplement the base gas supplied to the latter conduit.

Conduit 8 is provided with a flow control valve in the form of a butterfly valve 12 which is connected to a piston 13, movable in a cylinder 14, by the medium of linkage 15, 16 and 17. Cylinder 14 has connecting interiorly thereof at opposite ends the pipes 18 and 19 which terminate at open ends adjacent the end of a nozzle 20^a of a ratio controller 20.

Ratio controller 20 is of the general character disclosed in the Wunsch Patent No. 1,558,529. More particularly controller 20 includes upper and lower diaphragms 20^b and 20^c, respectively. The upper and lower sides of diaphragm 20^b are subjected to the fluid pressure at the upstream and downstream sides, respectively, or orifice 6, through the medium of pipes 21 and 22. A member 20^d rigidly connected to diaphragm 20^b bears against the upper side of nozzle 20^a. The lower and upper sides of diaphragm 20^c are subjected to the fluid pressures at the upstream and downstream sides of a restriction valve in the form of a butterfly valve 23 in conduit 8, through the medium of pipes 24 and 25, respectively. A member 20^e rigidly connected to diaphragm 20^c bears against the bottom side of nozzle 20^a. When fluid under pressure is flowing through nozzle 20^a controller 20 functions to balance the pressure drop across orifice 6 against the pressure drop across valve 23, and actuates valve 12 through movement of piston 13 to maintain a constant ratio between these pressure drops. Thus the peak shaving gas flowing in conduit 8 is maintained in a constant volumetric ratio to the base gas flowing in conduit 5.

The volumetric ratio between the base gas and peak shaving gas is determined by the adjustment of valve 23 through the medium of hand-

setting mechanism schematically depicted by numeral 26. Such hand-setting mechanism can be of any preferred form permitting adjustment of valve 23 to any selected position between closed and fully open positions.

Conduit 8 is additionally provided with a metering valve in the form of butterfly valve 27. Valve 27 is connected by suitable linkage 28, 29 and 30 to a piston 31 which moves in a cylinder 32. Cylinder 32 has connecting interiorly thereof, at opposite ends, pipes 33 and 34 which terminate at open ends adjacent the end of a nozzle 35^a of a pressure drop regulator 35.

Regulator 35 is provided with a diaphragm 35^b which is subjected on its lower and upper sides to the fluid pressures at the upstream and downstream sides, respectively, of valve 27, through the medium of pipes 36 and 37. A member 35^c rigidly connected to diaphragm 35^b bears against the bottom side of nozzle 35^a. A loading spring 35^d abuts at its lower end against the upper side of nozzle 35^a and at its upper end bears against an abutment 35^e. Regulator 35 functions in response to changes in the pressure drop across valve 27 to effect movement of piston 31 to adjust the valve 27 so that the pressure drop across the latter will be maintained constant.

Valve 27 is connected by suitable linkage 38, 39 and 40 to a corresponding metering valve in the form of a butterfly valve 41 in conduit 11. The linkage 38, 39 and 40 is so arranged and proportioned that upon a given adjustment of valve 27 valve 41 will be given a corresponding proportional adjustment, thereby maintaining the areas of opening of valves 27 and 41 in fixed ratio.

Conduit 11 is additionally provided with a flow control valve in the form of a butterfly valve 42, which is connected by suitable linkage 43, 44 and 45 to a piston 46 moving in a cylinder 47. Cylinder 47 has connecting interiorly therewith, at opposite ends, the pipes 48 and 49 which terminate at open ends adjacent the end of a nozzle 50^a of a pressure difference regulator 50.

Regulator 50 is provided with a diaphragm 50^b which is subjected on its upper and lower sides to the fluid pressures at the upstream and downstream sides of valve 41, respectively, through the medium of pipes 51 and 52. A member 50^c rigidly secured to diaphragm 50^b bears against the upper side of nozzle 50^a. A spring 50^d is interposed between the lower side of nozzle 50^a and an adjustable abutment 50^e. The degree of compression of spring 50^d may be initially manually adjusted in any suitable manner to preselect the value of pressure drop valve 41, and hence the angular position of valve 42, for any given adjustment of valve 41. Spring 50^d is subject to adjustment of its degree of compression by operation of a reversible electric motor 53, through the medium of reduction gearing 54 and an associated crank 55 to effect an increase and decrease in compression of such spring. As will be hereinafter more fully explained motor 53 is controlled by a B. t. u. controller generally designated by the encompassing broken line 56.

By-pass conduit 10 merges at its upstream end with conduit 8 at the upstream side of flow control valve 12 and at its downstream end with conduit 8 at a point between restriction valve 23 and metering valve 27. Conduit 10 is provided with a pressure regulator 57 having a valve seat 57^a, a valve plug 57^b, an operating stem 57^c and a diaphragm 57^d. Stem 57^c is connected to diaphragm 57^d and plug 57^b to move the latter relative to the seat 57^a in response to movement of

diaphragm 57^d. Diaphragm 57^d has a member 57^e secured to its upper surface and a pivotally supported lever 57^f bears against member 57^e. A weight 57^g adjustably carried on lever 57^f is provided to adjust the loading on the upper side of diaphragm 57^d. The lower side of diaphragm 57^d is subjected to the pressure of the mixed auxiliary gas and air in conduit 9 through the medium of a pipe 58.

10 Lever 57^f of regulator 57 is adapted to engage the movable contactor of an electric switch 59 which may be assumed to be normally biased to open-circuit position. The loading of regulator 57 by weight 57^g will move plug 57^b down and 15 off of seat 57^a when the pressure in conduit 9 falls appreciably below a predetermined value. Under such condition switch 59 will open under its bias. It may be assumed that when the pressure in conduit 9 exceeds said predetermined 20 value lever 57^f will assume the position depicted in the drawing wherein it holds switch 59 in closed position against its bias.

Switch 59 has its left-hand stationary contact connected through a conductor 60 to a junction 25 point X in an electrical network of B. t. u. controller 56. The right-hand stationary contact of switch 59 is connected to adjusting element 61^a of a rheostat 61. Rheostat 61 has a resistance element 61^b which has a single end terminal 61^c, and said rheostat has a contact 61^d adjacent but electrically isolated from the upper end of resistance element 61^b. Adjusting element 61^a is mechanically connected to valve 23 by 30 suitable linkage 62^a, 62^b and 62^c, through the medium of which it is adapted to be positioned on resistance element 61^b in accordance with the adjustment selected for valve 23. Terminal 61^c of resistance element 61 is connected through a 35 resistor 63, and normally closed contacts 64^a of a switch 64 to the right hand terminal of the resistance element 65^a of a potentiometer rheostat 65 of controller 56.

B. t. u. controller 56 is similar to that shown in the Schmidt Patent No. 2,238,606, issued April 15, 1941. Controller 56 has associated therewith a calorimetric device 66, which may be assumed to be of the type shown in the aforementioned patent. Calorimetric device 66 is supplied with a continuous sample of the peak shaving gas-air mixture flowing in conduit 9 through the medium 40 of a pipe 67.

The left-hand terminal of the resistance element 65^a of rheostat 65 is connected in series with a resistor 68 to junction point X and said resistance element has its right-hand terminal connected in series with a tank temperature compensating resistor RT, located in calorimetric device 66, a resistor 69, the resistance element 70^a of a potentiometer rheostat 70, a battery 71 and a 45 variable resistor 72. A resistor 73 is connected between junction point X and the point common between resistor RT and resistor 69.

50 Calorimetric device 66 is provided with an electro-thermocouple 74 comprising series connected cold and hot junctions CJ and HJ. Junction HJ is connected in series with the contacts 64^b of switch 64, galvanometer G, and contacts 64^c of said switch to the adjusting element 65^b of potentiometer rheostat 65. Junction CJ is connected to ground and to junction point X.

55 The point common between the right-hand contact of contacts 64^b and galvanometer G is connectable through contacts 75^a of a switch 75 to junction point X. The point common between galvanometer G and the right-hand contact of

contacts 64^c is connectable through contact 75^b of switch 75 and a standard cell SC to adjusting element 70^b of rheostat 70. Switches 64 and 75 are mechanically interlocked through a pivoted toggle lever 76 so that when switch 64 is closed switch 75 is open and vice versa.

Galvanometer G is mechanically connected to adjusting element 65^b of rheostat 65 and said adjusting element is mechanically coupled to the movable contactor 77^a of a switch 77 which has a pair of stationary contacts 77^b and 77^c. The arrangement is such that deflection of galvanometer G to either side of its neutral point will cause corresponding movement of adjusting element 65^a and contactor 77^a. In practice galvanometer G would not actually afford the drive, but control the device afforded drive from an auxiliary driving source as shown and described in the aforementioned Schmidt patent.

The aforementioned reversible motor 53 is connectable to a supply line L¹ of an electrical switch through a normally open switch 78 which is periodically closed through the medium of a rotating cam 79 driven by a motor 80 connected across supply lines L¹ and L² of said supply circuit. Contactor 77^a of switch 77 is connected to line L² and contacts 77^b and 77^c are connected to terminals T¹ and T², respectively, of motor 53. Motor 53 has a terminal T³ directly connected to supply line L¹.

Let it be assumed that with a base gas consisting of carbured water gas being supplied to conduit 5 at a preselected supply pressure that it is desired to mix with it peak shaving gas, consisting of a propane-air mixture, in such proportion that the mixed gas flowing in conduit 7 will consist of 10% peak shaving gas by volume. Valve 23 is given a setting through the medium of hand-setting mechanism 26 which will afford mixed gas having the aforementioned proportion of peak shaving gas. Ratio controller 28 will function in the manner aforescribed to adjust flow control valve 42 in the auxiliary gas conduit 8 so that the flow of the auxiliary gas will be proportional to the flow of base gas at all times. Pressure difference regulator 35 will function to maintain a constant pressure drop across metering valve 27. Valve 41 in air conduit 11 will be opened to the same degree as valve 27 so that the ratio of areas of opening of valves 27 and 41 remain constant. Controller 50 functions to adjust flow control valve 42 so that the flow of air in conduit 11 will produce a pressure drop across valve 41 depending on the loading of spring 50^d. With this loading fixed, flow of peak shaving gas through valve 27 and flow of air through valve 41 will then remain in fixed proportion. Changing the loading of spring 50^d changes the ratio of flows and the heating value of the mixture in conduit 9. If the pressure of the mixed gas flowing in conduit 7 is above a predetermined pressure, pressure regulator 57 will assume the "valve closed" condition depicted in the drawing and switch 59 will be closed as depicted.

With switch 59 closed, and valve 23 set for 10% or less peak shaving, contact 64^a will be in contact with terminal 64^c, and with contact 64^a closed, resistor 63 will be connected across resistor 68 and potentiometer 65, to thereby reduce the current flow through and the potentials across resistors 68 and 65. With valve 23 set for over ten per cent peak shaving, portions of rheostat 61 are included with resistor 63 in this parallel circuit reducing the potential across resistors 68 and 65 to a lesser extent. Resistance values of

rheostat 61 and 63 are selected so that the potential across resistors 68 and 65 are proportional to the value of heating value of the peak shaving mixture which will not cause problems in the utilization of the mixture of peak shaving gas and base gas. Thus, at 10% or less peak shaving, this potential would be equal to the potential generated by thermocouple 74 when the heating value of gas in conduit 9 had a heating value equal to that of the base gas. With valve 23 set for higher percentage of peak shaving, rheostat 61 might be in the position shown with section 61^c to 61^b included in the circuit, requiring a higher potential from thermocouple 74 to maintain slider 65^b at the control point.

The E. M. F. of thermocouple 74 in calorimetric device 66 of course varies in a well known manner in accordance with the variation in B. t. u. content of the auxiliary gas-air mixture supplied through sampling pipe 67. Change in E. M. F. of thermocouple 74 effects an unbalance in the potentials to which galvanometer G in controller 56 is subjected and its movable element (not shown) moves from its neutral position and effects a corresponding movement of adjusting element 65^b of rheostat 65 and contactor 77^a of switch 77 from their respective balance and center positions, which may be assumed to be those depicted in the drawing. Contactor 77^a when so moved engages with either contact 77^b or 77^c, depending upon the direction of movement of the movable element in galvanometer G. When contactor 77^a engages with contact 77^b circuit connections are thereby established for motor 53 to afford operation of the latter in one direction in small increments of rotation in response to the periodic closure of switch 78 by cam 79 which may be assumed to be continuously driven by motor 80. Similarly, when contactor 77^a engages with contact 77^c circuit connections are thereby established for motor 53 enabling its operation in the reverse direction in small increments of rotation under the control of switch 78.

Operation of motor 53, as aforescribed, effects a readjustment of the tension of spring 50^d in controller 50 so that the latter will thereafter function to afford a different degree of opening of valve 42 for the same degree opening of valve 41. Such change in degree of opening of valve 42 changes the volumetric proportion of air in the auxiliary gas-air mixture flowing in conduit 9, thereby effecting an increase or decrease in the heating value of such mixture as the case may be.

When the heating value of the adjusted auxiliary gas-air mixture approaches the value which controller 56 is set to maintain, the potentials to which galvanometer G is subjected approach a balance and when ultimately balanced the movable element of the galvanometer again attains its neutral position and adjusting element 65^b of rheostat 65 and contactor 77^a of switch 77 to attain their respective balance and center positions as depicted in the drawing. As a result, operation of motor 53 ceases until a condition of potential unbalance in galvanometer G again occurs.

The foregoing description of operation of course does not indicate the manner of functioning of the aforescribed potentiometer circuit of controller 56. For a more complete understanding of how controller 56 functions reference should be made to the aforementioned Schmidt patent.

The aforescribed condition of operation of

the system presupposes that the contacts of switch 64 are closed and that the contacts of switch 75 are open as depicted in the drawing. Closing of the contacts of switch 75 and opening of the contacts of switch 64 enables calibration of controller 56 and adjustment to compensate for deterioration of battery 71 as is fully explained in the aforementioned Schmidt patent. It will be noted that opening of switch contacts insures that adjustable rheostat 61 and resistor 63 will be disconnected from circuit regardless of the positioning of switch 59.

If during operation of the system the supply of base gas should completely fail, or fall to a very low value, pressure regulator 57 will respond to move to "valve open" position thereby opening by-pass conduit 10 around valves 12 and 23, and also effecting opening of switch 59. Opening of switch 59 effects disconnection of rheostat 61 and resistor 63 from the potentiometer circuit of controller 56.

When rheostat 61 and resistor 63 are disconnected from the potentiometer circuit of controller 56 the latter functions to maintain a higher heating value of the auxiliary gas-air mixture flowing in conduit 9. In other words, the effective control point of the controller is increased. Thus assuming that the controller before opening of switch 59 was functioning to maintain the auxiliary gas-air mixture at 540 B. t. u./cu.-ft., with such mixture comprising 10% by volume of the base gas-peak shaving gas mixture flowing in conduit 7, controller 56 will function upon opening of switch 59 to maintain the heating value of the auxiliary gas-air mixture at 700 B. t. u./cu.-ft. As indicated in the aforementioned Schmidt and Warner patent, when the gas supplied to consumer appliances consists of 100% peak shaving gas the latter must have a heating value of 700 B. t. u./cu.-ft. to insure satisfactory appliance utilization. Peak shaving at this latter heating value at less than 100% peak shaving is objectionable only due to economic consideration.

Thus controller 56 should be calibrated to maintain a heating value of 700 B. t. u./cu.-ft. with switch 59 open, assuming a base gas comprising carbured water gas with a heating value of 540 B. t. u./cu.-ft., and an auxiliary gas comprising propane having a heating value of 2500 B. t. u./cu.-ft. If other base gas, such as natural gas, is used, then the use of propane as the auxiliary gas requires that the control point of controller 56 be set to maintain a higher heating value, depending upon known inter-changeability factors.

With switch 59 closed, controller 56 will then function to maintain a heating value of the auxiliary gas-air mixture flowing in conduit 9 at a lower value as determined by what portion of resistance element 61^b of rheostat 61 is effectively in circuit. The position of resistance element 61^b which will be effectively in circuit is of course determined by the adjustment of adjusting element 61^a which is in turn determined by the adjustment of valve 23. Under normal conditions with supply of peak shaving gas scheduled on a basis of 10% by volume of the base gas-peak shaving gas mixture and with restriction valve 23 set to afford such proportion, adjusting element 61^a should be set to afford inclusion of that amount of resistance element 61^b, which together in series with resistor 63 will cause controller 56 to function to maintain a heating value of the auxiliary gas-air mixture flowing in con-

duit 9 at the heating value of the base gas. As will be appreciated when the mixing of peak shaving gas is scheduled on a higher proportion than 10% by volume of the resultant base gas-peak shaving gas mixture, restriction valve 23 will be opened to a further degree. Correspondingly adjusting element 61^a of rheostat 61, through the medium of linkage 62, 63 and 64, will be adjusted to include a greater amount of resistance element 61^b in circuit with the potentiometer circuit of controller 56, thereby effecting a corresponding increase in heating value of the auxiliary gas-air mixture which controller 56 will be set to maintain.

15 In order to stabilize potentiometer current independent of the condition of the parallel circuit including switch 59, rheostat 61 and resistor 63, a switch 64^a is included in this circuit. Switch 64^a is part of standardizing switch 64 which is 20 mechanically coupled to switch 75. In the drawing these switches are shown in the operating position. In the standardizing position 64 is opened and 75 closed. Galvanometer G is then 25 connected in series with standard cell SC, the left hand portion of resistor element 78^a of potentiometer 76 and resistor 69 across resistor 73, and such series connected combination is also 30 in parallel with the series combination of resistor RT, resistance element 65^a of potentiometer 65 and resistor 68, which latter series combination is likewise connected across resistor 73. The circuit including resistors 63 and 61 is open 35 circuited by switch 64^a. Battery rheostat 72 may then be adjusted to balance standard cell voltage against the voltage drop across this circuit as fully described in the aforementioned Schmidt patent, the setting of 70 being adjusted to produce balance of 65 at the control point when the 40 heating value of the peak shaving mixture is at the correct value for 100% replacement of base gas.

The system further comprises a potentiometer circuit 84 forming part of a heating value recorder. This circuit is similar to the circuit described in Schmidt patent and operates on the same thermocouple 74 forming part of calorimeter 66. A thermometer RT¹ forming part of the circuit is included in calorimeter 66. Arm 87^b of potentiometer is mechanically connected to an 45 indicator and recording pen (not shown) to give an indication and record of peak shaving mixture heating value.

The system further comprises a potentiometer circuit 84 for control of a B. t. u. recorder (not shown). This potentiometer circuit, which is in 50 certain respects similar to that aforementioned in connection with controller 56 will now be described.

A resistor 85 is connected at its left-hand end 55 through a conductor 86 to the point common to cold junction CJ of thermocouple 74 and the ground to which said junction is connected. Resistor 85 is connected at its right-hand end in series with resistance element 87^a of a potentiometer rheostat 87, a compensating thermometer resistor RT¹ in calorimetric device 69, and a resistor 88 to junction Z which is common to conductor 86 and its aforementioned left-hand. A resistor 89 is connected at its left-hand end to the point common between resistor RT¹ and resistor 88, and its right-hand end is connected in 60 series with resistance element 90^a of a potentiometer rheostat 90, a battery 91, and an adjustable resistor 92 to junction point Z. A galvanometer G¹ is connected at its left-hand side in 65

series with normally closed contacts 93^a of switch 93 to the point common between hot junction HJ of thermocouple 74 in calorimetric device 66 and the left-hand contact of contacts 64^b of switch 64. Galvanometer G¹ is connected at its right-hand side in series with normally closed contacts 93^b of rheostat 93 to adjusting element 87^b of rheostat 87. The point common between the right-hand contact of contacts 93^a and galvanometer G¹ is connectable through normally open contacts 94^a of a switch 94 to conductor 86. The point common between the right-hand contact of contacts 93^b and galvanometer G¹ is connectable through normally open contacts 94^b of switch 94, and in series with a standard cell SC¹ to adjusting element 90^b of rheostat 90.

Switches 93 and 94 are mechanically interlocked, as schematically depicted by the pivoted toggle lever 95, so that when switch 93 is closed switch 94 is open and vice versa.

Galvanometer G¹ may be assumed to have a movable element (not shown) which is deflected to either side of its neutral position in response to variations in E. M. F. of thermocouple 74 in a manner similar to that aforedescribed in connection with galvanometer G of controller 56. Thus a recording device, such as shown in the aforementioned Schmidt patent can be controlled so that a continuous record of instantaneous variations in heating value of the auxiliary gas-air mixture flowing in conduit 9 will be had.

I claim:

1. In a system for mixing a base gas and a supplementary gas in fixed preselected volumetric proportions, the combination with means affording flow of a base gas and a supplementary gas, of means responsive to variations in the rate of flow of base gas to maintain the flow of supplementary gas in a preselected volumetric proportion to the flow of base gas, calorimetric means responsive to variations in heating value of the supplementary gas, control means associated with said calorimetric means normally acting to maintain the heating value of the supplementary gas at a given value, means including pressure responsive means for effecting an increase in the volumetric proportionality of the supplementary gas to base gas when the supply of base gas and the preselected proportion of supplementary gas fails to meet the demand, and means under the control of said pressure responsive means for causing said control means to thereafter maintain the heating value of the supplementary gas at another given higher value.

2. In a system for mixing a base gas and a peak shaving gas in a fixed preselected volumetric proportion, the combination with means affording flow of a base gas and a peak shaving gas, of means responsive to variations in the rate of flow of base gas to maintain the flow of peak shaving gas in a preselected volumetric proportion to the flow of base gas, calorimetric means responsive to variations in heating value of the peak shaving gas, control means under the direction of said calorimetric means normally acting to maintain the heating value of the peak shaving gas at the same value as that of the base gas, means including pressure responsive means for effecting increase in the volumetric proportionality of peak shaving gas to base gas when the supply of base gas and the preselected proportion of peak shaving gas fails to meet the demand, and means under the control of said pressure responsive means for causing said control means to thereafter maintain the heating value of the peak

shaving gas at that value required for satisfactory appliance utilization when supplied with 100% peak shaving gas.

3. In a system for mixing a base gas and a supplementary gas in a fixed preselected volumetric proportion, in combination, means affording supply and flow of a base gas, means for effecting flow and mixing of a peak shaving gas and air comprising a conduit affording flow of peak shaving gas, means including valve means in said conduit responsive to variations in the rate of flow of base gas to maintain the flow of peak shaving gas in a preselected volumetric proportion to that of the base gas, a second conduit affording flow of air, means including a bypass conduit section around said valve means and a pressure responsive valve normally closing said conduit section whenever the pressure of the peak shaving gas-air mixture is above a given value and responding to decrease in pressure below said given value to open said conduit section and afford flow of peak shaving gas at an increased volumetric rate and means including valve means in said second conduit for normally maintaining the flow of air in constant volumetric proportion to that of the peak shaving gas, and means for controlling the heating value of the peak shaving gas-air mixture comprising calorimetric means continuously subjected to the peak shaving gas-air mixture, additional valve means in said second conduit controlled by said calorimetric means to afford change in the volumetric proportion of air to that of the peak shaving gas in accordance with instantaneous changes in the heating value of the peak shaving gas-air mixture and means under the control of said pressure responsive valve normally conditioning said calorimetric means to maintain the heating value of the peak shaving gas-air mixture at a given value whenever said conduit section is closed and affording in response to opening of said conduit section conditioning of said calorimetric means to maintain the heating value of the peak shaving gas-air mixture at another given higher value.
4. In a system for mixing a base gas and a liquid petroleum gas-air mixture in a fixed preselected volumetric proportion, in combination, means affording supply and flow of a base gas, means for effecting flow and mixing of a liquid petroleum gas and air comprising a conduit affording flow of a liquid petroleum gas, means including valve means in said conduit responsive to variations in rate of flow of base gas to maintain the flow of petroleum gas in a preselected volumetric proportion to that of said base gas, a second conduit affording flow of air, means including valve means in said second conduit responsive to variations in rate of flow of petroleum gas to normally maintain the flow of air in that volumetric proportion to the petroleum gas as will afford the same heating value of the petroleum gas-air mixture as that of said base gas, means including a bypass conduit section around the valve means in the first mentioned conduit and a pressure responsive valve normally closing said conduit section whenever the pressure of the petroleum gas-air mixture is above a given value and responding to decrease in pressure of the latter mixture below said given value to open said conduit section to afford increased volumetric rate of flow of petroleum gas, and means for controlling the heating value of the petroleum gas-air mixture comprising calorimetric means continuously subjected to the petroleum gas-air mixture, additional valve means in said second

conduit controlled by said calorimetric means to afford change in the volumetric proportion of air to that of the petroleum gas in accordance with instantaneous variations in the heating value of the latter mixture and means under the control of said pressure responsive valve normally conditioning said calorimetric means to maintain the heating value of the petroleum gas-air mixture at the aforementioned value whenever said conduit section is closed and affording in response to opening of said conduit section conditioning of said calorimetric means to thereafter maintain the heating value of the petroleum gas-air mixture at that value required for satisfactory appliance utilization when supplied with 100% petroleum gas-air mixture by volume.

5. In a system for mixing a base gas and a supplementary gas in a fixed preselected volumetric proportion, in combination, means affording supply and flow of a base gas, means for effecting flow and mixing of an auxiliary gas and air comprising a conduit affording flow of an auxiliary gas, a second conduit affording flow of air, means responsive to variations in the rate of flow of base gas including a valve in the first mentioned conduit and a fixed but adjustable valve in said first mentioned conduit for maintaining flow of auxiliary gas in a preselected volumetric proportion to that of the base gas, means including a conduit section providing a by-pass around the first mentioned and adjustable valves in the first mentioned conduit and a pressure responsive valve acting to maintain said conduit section closed whenever the pressure of the auxiliary gas-air mixture is above a given value and responding to decrease in pressure of the auxiliary gas-air mixture below the aforementioned value to open said conduit section to provide increased rate of flow of auxiliary gas and means responsive to variations in the rate of flow of auxiliary gas including a third valve in said first mentioned conduit and a fourth valve in said second conduit for normally maintaining the flow of air in a preselected constant volumetric proportion to that of said auxiliary gas, and means for controlling the heating value per unit volume of the auxiliary gas-air mixture comprising a fifth valve in said second conduit, a regulator having control point adjusting means and being responsive to variations in pressure drop across said fourth valve for controlling the adjustment of said fifth valve, calorimetric means continuously subjected to the auxiliary gas-air mixture and responding to instantaneous variations in heating value thereof to effect through the medium of said control point adjusting means readjustment of the control point of said regulator and means subject to control by said pressure responsive valve normally conditioning said calorimetric means for maintaining a preselected heating value of the auxiliary gas-air mixture whenever said by-pass conduit section is closed and affording in response to opening of said by-pass conduit a predetermined increase in heating value of the auxiliary gas-air mixture thereafter maintained by said calorimetric means.

6. In a system for mixing a base gas and a supplementary gas in a fixed preselected volumetric proportion, in combination, means affording supply and flow of a base gas means for effecting flow and mixing of an auxiliary gas and air comprising a conduit affording flow of an auxiliary gas, a second conduit affording flow of air, means responsive to variations in the rate of flow of base gas including a valve in the first mentioned conduit and a fixed but adjustable valve in said first mentioned conduit for maintaining flow of auxiliary gas in a preselected volumetric proportion to the base gas, means including a conduit section providing a by-pass around the first mentioned and adjustable valves in the first mentioned conduit and a pressure responsive valve acting to maintain said conduit section closed whenever the pressure of the auxiliary gas-air mixture is above a given value and responding to decrease in pressure of the auxiliary gas-air mixture below the aforementioned value to open said conduit section to provide increased rate of flow of auxiliary gas and means responsive to variations in rate of flow of auxiliary gas including a third valve in the first mentioned conduit and a fourth valve in said second conduit for maintaining the flow of air in constant volumetric proportion to that of said auxiliary gas, a fifth valve in said second conduit, a regulator responsive to variations in pressure drop across said fourth valve to effect adjustment of said fifth valve and having control part adjusting means under the control of an electric motor, calorimetric means responsive to variations in heating value of the auxiliary gas-air mixture comprising a measuring circuit including a potentiometer type rheostat having its adjusting element positioned in accordance with changes in the heating value of the auxiliary gas-air mixture and switch means under the control of the rheostat adjusting element for controlling the operation of said electric motor, a resistor, and means including a switch under the control of said pressure responsive valve for connecting said resistor in parallel with said rheostat whenever the by-pass conduit section is closed to normally condition said calorimetric means for maintaining a given heating value of the auxiliary gas-air mixture, said switch upon opening of said by-pass conduit section affording disconnection of said resistor to thereby condition said calorimetric means to thereafter maintain a preselected higher heating value of the auxiliary gas-air mixture.
